UNITED STATES PATENT OFFICE.

CYRUS B. WELLS, OF SCRANTON, PENNSYLVANIA, ASSIGNOR TO THE SCRANTON BUTTON COMPANY, OF SCRANTON, PENNSYLVANIA, A CORPORATION OF PENNSYLVANIA.

DIE FOR MOLDING PLASTIC MATERIAL.

Application filed January 11, 1924, Serial No. 625,611. Renewed March 10, 1926.

To all whom it may concern:

Be it known that I, CYRUS B. WELLS, a citizen of the United States, residing at Scranton, in the county of Lackawanna and State of Pennsylvania, have invented certain new and useful Improvements in Dies for Molding Plastic Material, of which the following is a specification.

This invention relates to improvements in dies for molding flat objects, such as phonograph records, from plastic material containing a binder which softens with heat and is hard at normal temperatures. Dies for molding this material are usually channeled so that steam may be circulated through them to heat them while the dies of a pair are separated, and the cold water may be circulated through them to chill and set the material after it has been pressed between the dies.

It is customary to form the die plates of steel and to cut the channels in the backs of the plates; but this is an expensive process, especially when the channels are of any other form than circular, and besides, the corrosive action of the fluids on the machined surfaces of the channel walls causes the ribs between the channels to deteriorate much more rapidly than they would if the channels were of cast metal.

In carrying out the invention, I provide a die-plate, of steel, with a flat under surface and with a flange at its periphery, and a channel-plate, of cast metal, which is machined on its opposite sides and at its periphery and adapted to fit fluid-tight within the die-plate. The channels in the channel-plate are preferably formed with walls which diverge from the bottoms of the channels upwardly, and the underside of the die-plate closes the open sides of these channels when the plates are fitted together. Thus, the widest parts of the channels are next to the die-plate and a large surface of the latter is exposed directly to the heating and cooling fluids which flow through the channels. The channels may be cast in any desired form, and their walls are not machined. Thus, there is a saving in the cost of forming the channels, and the unfinished walls of the channels offer greater resistance to the corrosive action of the fluids than would machined walls, thus prolonging the life of the partitions which support the die plate. Furthermore, the channel-plate

braces the die-plate so that there is less danger of buckling the latter while being calked in place in the die frame.

In the accompanying drawing, which illustrates the invention,

Fig. 1 is a plan view of a die and die frame embodying my invention, the channels in the channel-plate being shown in dotted lines;

Fig. 2 is a section on the line 2—2 of Fig. 1; and,

Fig. 3 is a plan view of the channel-plate.

Referring to the drawing, *a* represents a die frame adapted to be secured in a press, *b* indicates the die-plate, and *c* represents a channel-plate interposed between the die plate and the frame. The frame has a circular recess 1, adapted to receive the die and channel plates. The die plate *b* is flat and is made as thin as is practicable, and it is provided with a flange 2, adapted to fit fluid-tight within the peripheral wall 1^a of the recess 1. The channel plate *c* may be of cast metal, machined on its opposite sides and at its periphery, and it is adapted to fit fluid-tight within the annular flange 2 of the die-plate with the open sides of the channels 3 facing the body of the die-plate. The die-plate thus rests against the ribs 4 and forms a closure for the channels. The two plates have central openings which fit fluid-tight around the central boss 6 on the frame.

In assembling the parts the channel-plate is pressed into the die-plate and the latter is then pressed into the recess in the die frame and calked in place. The channel-plate has openings 3^a extending through it at certain points in the channels, and these openings align with openings 7 in the die frame which communicates with passageways 5, bored in the frame, for conducting water and steam to and from the channels.

Usually, die plates are formed of steel, with channels cut in their undersides, leaving ribs integral with the plates. This is expensive, especially when the channels have to be cut in forms other than circular, as, for instance, in the spiral form shown in the drawing, and besides, the corrosive action of the steam and water on the machined surfaces of the channels is destructive of the dies. The channel-plate in the die of the present invention may be cast with channels of any form, saving all machining of the channels, and the metallic oxide on the un-

finished walls of the channels will resist the corrosive action of the fluids to a much greater extent than will the surfaces of machined walls, thereby prolonging the life 5 of the ribs or partitions between the channels. As a means of protecting from corrosion the machined surfaces of the die-plate and channel-plate which may be exposed to the fluids, a coating of copper may be deposited upon the inner face of the former, including its flange, and the surfaces of the latter.

It is to be noted that the channel walls diverge toward the die-plate so that a relatively large area of the die-plate comes in direct contact with the fluids, and the sloping ribs form a more rigid support for the die-plate than the ribs of the usual form, with parallel sides, cut in the underside 29 of the die-plate.

The structure described also provides a leak-proof joint between the die-plate and the die frame at the flange 2. In order that leakage of steam or water from the 25 channels may take place, the fluid must pass from one of the outer channels between the edge of the channel-plate and the flange 2, thence between the bottom of said flange and the bottom of the recess 1, and thence upwardly between the outer surface of the flange and the peripheral wall 1^a of the recess 1. These parts are all forced together while cold, making a fluid-tight joint. When steam is admitted to the channels, 35 the die-plate and the channel-plate both expand. This causes an outward pressure of the flange on the die-plate against the peripheral wall of the recess 1, and an outward pressure of the channel-plate against the inner wall of the flange, thereby keeping a perfect seal between the parts while they are heated.

In the drawing, the channels are arranged 45 in spiral form, with inlets and outlets arranged as more particularly described in the co-pending application of Sylvester and Wells, Serial No. 661,700, filed September 8, 1923; but it will be evident that the chan-

nels may take any desired form and that the cost of making the die is not affected 50 by the form of the channels.

What I claim is:

1. A die for molding plastic material comprising a die body, a channel-plate resting on said body and having channels and intermediate ribs on the side opposite said body, and a die-plate resting on said ribs and secured to the body.

2. A die for molding plastic material comprising a die body, a cast metal channel-plate resting on said body and having channels and intermediate ribs on the side opposite said body, and a die plate resting on said ribs and secured to the body.

3. A die for molding plastic material comprising a die body, a channel-plate resting on said body and having channels and intermediate ribs on the side opposite said body, the side walls of said channels diverging from the bottoms of the channels, and a die-plate resting on said ribs and secured to the body.

4. A die for molding plastic material comprising a die body, a cast metal channel-plate resting on said body, a cast metal channel-plate resting on said body and having channels and intermediate ribs on the side opposite said body, the side walls of said channels diverging from the bottoms of the channels, and a die-plate resting on said ribs and secured to the body.

5. A die for molding plastic material comprising a die-body having an annular recess, a die-plate having a flange fitting within said recess, and a channel plate fitting within said flange and having channels closed at one side by the die plate.

6. A die for molding plastic material comprising a die body having an annular recess, a die-plate having a flange fitting within said recess, and a cast metal channel plate fitting within said flange and having channels closed at one side by the die-plate.

In testimony whereof I hereunto affix my signature.

CYRUS B. WELLS.
